UNITED STATES PATENT OFFICE.

FRANK F. LANDIS, OF WAYNESBORO, PENNSYLVANIA.

ELECTRIC CLOCK.

1,130,092.

Specification of Letters Patent.

Patented Mar. 2, 1915.

Application filed January 27, 1906, Serial No. 298,224. Renewed May 18, 1911. Serial No. 628,131.

To all whom it may concern:

Be it known that I, FRANK F. LANDIS, a citizen of the United States, residing at Waynesboro, in the county of Franklin and State of Pennsylvania, have invented certain new and useful Improvements in Electric Clocks, of which the following is a specification.

My said invention consists in certain improvements in the details of construction and arrangement of parts of secondary clocks, forming a part of an electric clock system, whereby such a clock is provided of comparatively few parts, which are easily fitted and not liable to get out of adjustment, and one which is comparatively inexpensive and durable in use; and, further, one wherein the time required for the movement of the minute hand over each space 20 may be regulated as desired, all as will be hereinafter more fully described and claimed.

Referring to the accompanying drawings which are made a part hereof and on which 25 similar reference characters indicate similar parts, Figure 1 is a rear elevation of a secondary clock movement embodying my said invention, the regulating devices being shown in section and the master clock indicated in front elevation. Fig. 2 an end 30 elevation of the same on a smaller scale as seen when looking in the direction indicated by the arrows from the dotted line 2-2 in Fig. 1, and Fig. 3 an underside 35 plan.

In said drawings the portions marked A represent the frame for supporting the various parts of the mechanism, B the operating lever and C a cylinder constituting the operating weight and containing the regulating mechanism.

The frame A is preferably a cast, skeleton frame of suitable size and has transversely projecting studs a and a' near diagonally opposite corners, to the outer ends of which a bar A' is secured by screws a^5 , a^6 . The main arbor is journaled at one end in a suitable bearing in said frame and at the other end in a bearing in said bar A' . The train of clock gearing comprises the operating ratchet wheel 8 mounted on a shouldered sleeve 9 and secured to the arbor 1 by friction through the spring yoke 10, which is mounted to bear between the side of said wheel and a pin 11 in said ar-

bor. A pinion 12 is mounted on arbor 1 and meshes with a gear wheel 13 on a stud shaft 14. Said gear 13 has a pinion 15 integral therewith, which meshes with a gear 16 mounted on the sleeve 4, which is mounted on arbor 1 and carries the hour hand 3, while the minute hand 2 is mounted on the outer end of arbor 1, the gearing being so proportioned that the rotation of sleeve 4 is one-twelfth the speed of the rotation of arbor 1, as is usual in clock gearing. A horizontal projection A^2 is formed at the rear end of frame A and the electro-magnets 5 and 6, and also a shunt coil 7, which may be used when needed, are mounted 70 thereon.

The operating lever B is mounted upon a pivot b which extends through bearings in the frame A at one end and the bar A' at its other end. An armature B' is mounted 75 on its rear end within the field of the magnets 5 and 6. A double-ended pawl B^2 is pivoted to said lever B near its forward end on a pivot b' and has a transverse pin b^2 rigidly secured therein which projects 80 through a short segmental slot in said lever B. This arrangement permits said pawl to rock on its pivot b' sufficiently to clear its rear point from the teeth of the ratchet wheel 8, with which it is adapted to engage, 85 each time this end of said lever is lifted. A second pawl B^3 is mounted upon a pivot b^3 on a suitable projection on the frame and is adapted to engage behind the tooth of the ratchet wheel 8 which is engaged on its front side by the rear end of the pawl B^2 . A link B^4 is pivotally connected at its upper end with the outer end of the transverse pin b^2 in pawl B^2 and is pivotally connected at its lower end to the lever B^5 , which is mounted upon a pivot b^4 on a suitable projection 90 a^2 on one side of the frame A.

The cylinder C is adapted to contain a fluid and is mounted upon the rear end of lever B^5 by means of links c which are pivoted at their upper ends to the opposite sides of said cylinder on projections c' and at their lower ends are mounted on opposite ends of a pivot rod c^2 which passes through said lever B^5 . A piston C' is mounted with in said cylinder upon the lower end of a sleeve C^2 being connected to said sleeve by means of a yoke or arms c^3 . Said sleeve C^2 passes through the head of cylinder C and is fixed at its upper end in an overhanging 110

arm A³ which extends over from the frame A. Said piston C' is provided with a central aperture or by-pass c⁴. A disk valve c⁵ is mounted upon the lower end of a screw-threaded rod C³, which is reduced in size 5 for a short distance to form a guide for said valve c⁵ to slide freely upon, being of such length that said valve may always lift to a height that will open the by-pass c⁴ to its full size when the cylinder C is lifted by 10 the power of the magnets. The reduced portion of rod C³ extends through the center of valve c⁵ and at its lower end has a transverse pin (or a nut) forming a stop c⁶. Said rod is mounted in sleeve C², which is 15 internally screw-threaded, and its upper end projects through said sleeve to above the arm A³ and has a transversely extending lever c¹⁴ by which it may be turned. A stop 20 consisting of an upwardly extending pin a⁴ is mounted in the top of the arm A³ in position to limit the turning of said screw-threaded rod C³ at a point where the stop c⁶ under the valve at lower end of said rod 25 will just allow valve c⁵ to be seated upon the top of the piston to close the by-pass c⁴ therein. Thus by turning said lever away from said stop a⁴ said stop c⁶ will be gradually raised above the top surface of the 30 piston and not allow the valve c⁵ to be seated to close the by-pass, so that when the cylinder C drops a portion of the fluid will pass under the valve and down through the by-pass. The farther lever c¹⁴ is moved 35 from stop a⁴ the larger will be the opening under the valve to the by-pass, and by moving it in the opposite direction it will be diminished, or closed altogether, as will be readily seen.

40 The operation of my said invention is as follows: The parts being assembled and adjusted as shown and described, the circuit-closer will be arranged to be operated at predetermined periods, as at one minute intervals, by the master-clock M, in the well-known manner. By the use of my governing device the intervals can be longer if desired, the longer the interval the less the work required of the master-clock to close 45 the circuit. It will, however, require a stronger magnet to lift a weight sufficient to propel a secondary clock a longer period of time, as will be readily understood. The magnets 5 and 6 are energized by the closing 50 of said circuit and the closing of said circuit will operate to draw down armature B', which tilts lever B upon its pivot b and lifts its opposite end, raising the rear end of pawl B² out of engagement with the tooth of the ratchet wheel 8 with which it has been engaged, at the same time dragging the forward end until it falls behind the next tooth. The circuit being then broken, the weight of 55 the cylinder C and its connections operates 60 through the lever B⁵ and the connecting link B⁴, to draw the forward end of said lever B downwardly, and through the forward end of pawl B² to advance the ratchet wheel 8 the distance of one tooth. As the lever B falls and the ratchet wheel advances, the rear end of said pawl B² also falls in front of the next tooth behind its point and prevents the forward movement of said wheel for more than the space of one tooth. Pawl B³ also falls behind said tooth and serves to 65 prevent any possible backward movement of the ratchet wheel when the lever B is again raised and the pawl B² lifted upward to allow its lower end to drop over the next tooth of the ratchet wheel. I have mounted 70 a weight W on a projecting end of lever B⁵ on the opposite side of its pivot b⁴ from the end with which cylinder C is connected, said weight being of sufficient gravity to 75 counterbalance all of the weight carried on the other end of the lever not needed to operate the mechanism, thus enabling said mechanism to be operated by the use of a minimum electric power. Heretofore in 80 such clocks, the operation of the minute hand from its position to mark one minute to that to mark another minute has been practically instantaneous, the hand jumping as the mechanism is operated from one point to the next. This is undesirable, especially in the 85 case of a large size secondary clock. It will be readily understood that if the movement from start to stop is slow or gradual, so that it requires nearly the entire interval to move the minute hand through the space on the 90 dial indicating the time between the operations of the magnets, the clock will more readily indicate the fraction of a minute and will be practically a regular clock-like movement. In order to provide for the 95 gradual or slow movement of the parts, and in order to use a cylinder of small dimensions, I place within the cylinder C a quantity of fluid or liquid of any character found suitable, glycerin being commonly used. But 100 when the space in which a clock movement is placed will permit the cylinder C may be of much greater size and capacity so that the same results are obtained by the air flowing 105 through the by-pass, eliminating the use of a liquid entirely. In operation, the cylinder C, after being elevated by the magnets and transferring a portion of the fluid below the piston C' to above said piston, will take the 110 time to descend that is required for the fluid to flow through the by-pass from above the piston C' to below it, which is regulated or determined by the size of the by-pass, the variation of which is accomplished by varying 115 the size of the opening under valve c⁵. Thus, by regulating the size of the by-pass c⁴, through the screw-rod C³ and the valve c⁵ on its lower end, the falling of the weight and the consequent advancement of the 120 ratchet wheel 8 and the moving forward of 125 the ratchet wheel 8 and the moving forward of 130

the hands upon the arbor through the dial train above described may be prolonged over the space of time desired, so that said hands move gradually with a regular clock-like movement. It is desirable, however, in order to avoid any possibility of this movement extending over the period of a minute that it should be regulated to be completed in a period a few seconds less than a minute or whatever the period of time may be. This can be accurately adjusted through the medium of the screw-rod C³ and the valve c⁶ on its lower end, as will be readily understood. A secondary clock movement is thus provided without springs and with comparatively few parts and one which will be always positive and reliable in its movement, being operated in its advance movement wholly through the medium of a weight and only depending upon the electric power to lift said weight and the operating pawls back over the teeth of the operating ratchet wheel. To keep the secondary clocks in exact time with the master-clock the opening through the by-pass must be sufficient to allow the cylinder, which is the driving weight of the clock, to drop its full distance before the circuit is again closed for the next movement of the clock. It will be understood from the foregoing that the governing device has no part in improving the time keeping quality of a secondary clock, but in the case of large secondary clocks, such as are placed in towers, the hands, especially the minute hand, which jumps from one minute to the next and stops very suddenly, produces unnecessary jars or shocks, which produce an unpleasant sound and in addition the hand does not have a regular clock like movement, all of which objections this governing device overcomes.

Having thus fully described my said invention, what I claim as new and desire to secure by Letters Patent, is:—

45 1. In an electric clock, the combination, of the arbor, the dial train, the toothed ratchet wheel, a pivoted lever having an armature upon one end and a double ended pawl pivoted near its opposite end, each end of which has a point adapted to engage with opposite sides of teeth on said ratchet wheel and being mounted to have a limited pivotal movement on said lever, a weight connected with said lever for operating said ratchet wheel through said pawl in one direction, and magnets mounted adjacent to the armature on its opposite end to operate it in the opposite direction, substantially as set forth.

60 2. In an electric clock mechanism, the combination with the dial train, of a ratchet wheel for operating the same, a pivoted lever carrying a double ended pawl pivoted thereto both ends of which are adapted to engage with the opposite sides of different teeth on said ratchet wheel, a pin secured

to said pawl and extending through a slot in said lever at one side of the pivot on which said pawl is mounted, a link connecting said pin with a weight, an armature on the opposite end of said lever, magnets arranged adjacent to said armature, and means for energizing said magnets at predetermined periods, substantially as set forth.

3. In an electric clock, the combination of a dial train, a toothed ratchet wheel for operating the same, a pivoted lever adjacent to the upper edge of said ratchet wheel, a double ended pawl pivoted on said lever to engage with said ratchet wheel, an armature on said lever, magnets adjacent to said armature, a weight pivotally connected with the driving end of said pawl, and means for regulating the time required for said weight to fall, substantially as set forth.

4. In an electric clock, the combination of a dial train, an operating ratchet wheel, the operating mechanism comprising an oscillating lever, a pawl pivoted on said lever for engaging said ratchet wheel, electric devices for operating said lever in one direction, a weight pivotally carried by said pivoted pawl for operating said lever in the other direction, and a regulating device for controlling the fall of said weight, whereby it may be limited to the time desired, substantially as set forth.

5. In an electric clock, the combination of a dial train, a ratchet wheel connected therewith, means for operating said ratchet wheel comprising an oscillating lever, a pivoted pawl mounted on said lever adapted to engage with the teeth of said ratchet wheel, an armature on said lever, magnets adjacent to said armature, and a weight pivotally connected to the pivoted pawl on said lever, said weight being controlled in its descent by a dash-pot regulator, whereby the movement of said mechanism may be timed as desired, substantially as set forth.

6. In an electric clock, the combination of the dial train, the ratchet wheel for operating the same, an oscillating lever carrying a double-ended pivoted pawl engaging with said ratchet wheel, an armature and magnets for operating said lever in one direction and a weight connected with a dash-pot regulator and pivotally attached to the driving end of said pawl for operating it in the other direction, substantially as set forth.

7. In an electric clock, the combination of the dial train, the ratchet wheel for operating the same, an oscillating lever carrying a pawl engaging with the teeth on said ratchet wheel, an armature on one end of said lever, magnets adjacent to said armature, a connection running from the opposite end of said lever to another pivoted lever, said pivoted lever, a cylinder carried

upon one end of said last mentioned lever containing a fluid, a piston supported by a part of the frame and mounted in said cylinder and formed with a by-pass, and a 5 valve for regulating the size of said by-pass, substantially as set forth.

8. In an electric clock, the combination of the mechanism for moving the dial train forward comprising a weight in the form of 10 a cylinder containing fluid and a retarding means therefor comprising a piston with an adjustable by-pass mounted in said cylinder and carried by a fixed support, substantially as set forth.

15 9. In an electric clock, the combination of the dial train, the ratchet wheel for operating the same, an oscillating lever carrying a pivoted driving pawl engaging with said ratchet wheel, a driving weight carried by 20 said pawl on the driving side of its pivot, an armature and magnets for operating said lever in one direction and said driving

weight for operating it in the other direction, substantially as set forth.

10. In an electric clock, the combination 25 of a dial train, a ratchet wheel connected therewith, the operating mechanism comprising an oscillating lever, a double ended pawl pivoted on said lever for engaging said ratchet wheel, electric devices for operating 30 said lever in one direction, a weight pivotally connected to the driving end of said pawl for operating said lever in the other direction, and a regulating device for controlling the time of the fall of said weight, 35 substantially as set forth.

In witness whereof, I have hereunto set my hand and seal at Waynesboro, Pennsylvania, this 12th day of January, A. D. nineteen hundred and six.
